CLAIM

The ornamental design for a three dimensional landscaped chess board, as shown and described.

DESCRIPTION

FIG. 1 is a perspective view of a three dimensional landscaped chess board, showing my new design, the bottom being plain and unornamented;

FIG. 2 is a top plan view thereof;

FIG. 3 is a front elevational view thereof;

FIG. 4 is a rear elevational view thereof;

FIG. 5 is a left side elevational view thereof; and,

FIG. 6 is a right side elevational view thereof.
